(57) CLAIM

The ornamental design for a nail lamp as shown and described.

DESCRIPTION

FIG. 1 is a perspective view of a nail lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 5; and,

FIG. 11 is a perspective view of the nail lamp, shown in a foldable position.

The dash-dash broken lines in the figures illustrate portions of the nail lamp that form no part of the claimed design. The short-dash-long-dash broken lines shown in FIGS. 1, 5, 9 and 10 depict the bounds of the enlarged views and form no part of the claimed design.
